UNITED STATES PATENT OFFICE.

BERNARD A. STERLING, OF CHICAGO, ILLINOIS.

HAIR-WAVER.

1,347,830.

Specification of Letters Patent. Patented July 27, 1920.

Application filed September 15, 1919. Serial No. 323,762.

To all whom it may concern:

Be it known that I, BERNARD A. STERLING, a citizen of the United States, residing at Chicago, in the county of Cook and 5 State of Illinois, have invented a certain new and useful Improvement in Hair-Wavers, of which the following is a full, clear, concise, and exact description, reference being had to the accompanying drawings, forming a part of this specification.

My invention relates to improvements in hair waving devices and has special reference to a device for producing more artistic "Marcel waves" upon the head of the user 15 than has been possible without special manipulation and the application of heat. In other words, my device is especially adapted for use upon the head to automatically produce artistic Marcel waves and without 20 heat.

The Marcel wave is a peculiar wave in that the individual hairs which constitute the wave as a whole each has a double wave or curvature. In other words, if the wave 25 as a whole be laid upon a flat surface, each hair of the wave will be found to extend in undulations vertical to the surface and a second series of undulations substantially parallel to the surface.

So far as I am informed, no Marcel wave 30 of this character has hitherto been produced without heat and with a simple curler upon the head. It is well known to those skilled in the art that it requires long practice and 35 careful training to be able to produce Marcel waves which are in any sense artistic and not mere round waves or curls.

By means of my invention I am not only 40 enabled to automatically produce artistic Marcel waves, but I add greatly to the artistic appearance of the waves in two very important particulars; first I produce a pleasing soft effect, or an effect of depth, especially to the depressions of the wave, 45 and I produce a pronounced sharpness to the transverse crests of the wave which eliminates the stiffness and solidarity of what may be termed the ordinary or unartistic Marcel waves.

I accomplish these desirable results and 50 many others substantially automatically by means of the waver of my invention.

My invention consists of a narrow flat 55 elongated member upon which the strand of hair of which the wave is to be produced is wound. This member comprises an elong-

gated flat base provided with a central longitudinal projection on its upper side. The longitudinal edges of the base are preferably, though not necessarily, formed in a 60 series of corrugations or teeth. The strand of hair is wound on this member beginning at one end and ending at the other and then a forming member having a central slot for receiving the projection on the base is forced 65 down upon the hair to depress the hair upon both sides of said longitudinal projection, thus forming the body of wound hair into a relatively sharp ridge along a longitudinal line which crosses the several turns 70 or winds at an angle. The free edge of the projection may be V-shaped to accentuate the sharpness of the ridges formed. Means are provided for holding the forming member clamped in position the requisite time 75 for producing the wave. Finally the forming member is removed and the strand unwound from the base member and upon loosening it up the wave is produced, the transverse depressions of which are soft by 80 reason of the alternative depressions and projections on the edges of the base member and the crests of the waves have more or less sharply defined ridges extending 85 across them. Both of these features are the goal of all hair workers who desire to excel in the making of Marcel waves.

My invention will be more readily understood by reference to said drawings, in which:

Figure 1 is a side elevation of my improved waver;

Fig. 2 is a perspective view of the device, the forming member being raised from the base member;

Fig. 3 is a cross sectional view on the line 3—3 of Fig. 1, showing the hair in position thereon; and

Fig. 4 is a fragmentary perspective view of a Marcel wave such as is produced by 100 the use of my device.

In said drawings, 1 is the base member. This member is flat, long and relatively narrow. Its lateral longitudinal edges are preferably corrugated, being formed of 105 alternating preferably rounded projections 2 and depressions 3, providing what may be termed toothed edges.

Upon the upper face of the base is provided a transversely central longitudinally 110 extending thin projection or rib 4. This rib does not extend the full length of the base

but may extend the length of the corrugations on the edges. The ends 5 and 6 of the base extend beyond the corrugations and I provide means on these ends for securing the forming member 7 in place for clamping the hair upon the base.

The forming member 7 is substantially as wide as the base and has a central longitudinal slot 8 adapted to receive the projection 4.

10 As best shown in Fig. 3, the slot 8 is wider than the thickness of the projection 4 to provide space for the hair 9 between the edges of the slot and the projection 4. As shown in said figure, one function of the
15 forming member is to press the turns of the wound strand of hair down over the upper edge 10 of the projection 4. In doing this it also presses the hair down into the re-entrant corners or angles between the base
20 and the projection 4.

The result of this forming of the hair down over the projection 4 is to accentuate the crest 11 of the Marcel wave 12 shown in Fig. 4.

25 The transverse depressions 13 of the Marcel wave 12 contain the portions of the strand which engage the transverse edges or the teeth 2 and the depth at these points of the wave is increased due to the engagement of some of the hairs in the depressions of the corrugations and others adjacent thereto with the projections 2 on the edges of the base member.

For making the ridges 11 even more pronounced I make the free edge 10 of the ridge 4 V-shaped as shown, forming it to a relatively sharp but smooth edge, and I incline the inner edges of the slot 8 in the forming member in a similar direction.

40 I preferably offset the ends 14 and 15 of the forming member 7 toward the base, thus providing a space 16 for the hair, beneath the central part of the member 7, when in position, with its ends resting on the ends 45 of the base. To prevent any possibility of any threads of hair becoming caught in the device, I prefer to make the member 7 freely removable or separable from the base and for holding it in clamping position I provide 50 strap-like members 17 and 18 preferably secured on the ends 5 and 6 of the base member and adapted to receive the ends 14 and 15 respectively of the forming member 7 beneath their upper walls. The member 55 17 is preferably fixed in position on the end 5 and is held against removal by lateral projections 19 on the end of the base 1. The strap 18 is slidable on the base and is held against complete removal by similar lateral 60 projections 20. The ends 14 and 15 of the forming member 7 are inclined or tapered to assist in entering them beneath the straps 17 and 18.

In placing the member 7 upon the device, 65 the strand of hair having been wound

around the base, the end 14 is entered beneath the strap 17, the member 7 being inclined at this time in relation to the base to permit the free entering of the end 14, and then the opposite end is forced down into contact with the opposite end of the base, thereby compressing the hair and forcing it down upon the opposite sides of the longitudinal projection 4 and then the strap 18 is pushed inwardly over the end 15. The pressure exerted to hold the member 7 down on the hair prevents the strap 18 being jarred off and the device remains in clamped condition until the strap 18 is slipped back and the member 7 released. 70 75 80

As many modifications of my invention will readily suggest themselves to one skilled in the art I do not limit or confine my invention to the specific structure herein shown and described.

I claim:

1. In a device for producing Marcel waves in hair, an elongated flat base member around which the strand of hair to be waved is adapted to be wound, a longitudinally extending thin projection or rib on the upper face of the base, a forming member for forcing the hair down toward the base on each side of said projection, and means for retaining the forming member in clamping position. 90

2. In a device for producing Marcel waves in hair, an elongated base member around which the strand of hair to be waved is adapted to be wound, a central longitudinally extending thin projection or rib on the upper face of the base, a slotted forming member for forcing the hair down toward the base on each side of said projection, and means for retaining the forming member in clamping position. 105 100

3. In a device of the class described, an elongated base member around which the strand of hair is adapted to be wound, a longitudinally extending central rib on the 110 upper face of the base, the free edge of said rib being V-shaped, a forming member for forcing the hair down toward the base on each side of said projection, and means for retaining the forming member in clamping 115 position.

4. In a device of the kind described, an elongated base member around which the strand of hair is adapted to be wound, a central longitudinal rib or projection on the upper face of the base, a slotted forming member for forcing the hair down toward the base on each side of said projection, the free edge of such projection being V-shaped and the adjacent walls of the slot in the forming member being similarly inclined, and means for retaining the forming member in clamping position. 120 125

5. In a device for producing Marcel waves in hair, an elongated flat base member 130

around which the strand of hair is adapted to be wound, the lateral edges of said base member being provided with alternating projections and depressions, a central longitudinally extending rib or projection on the upper face of the base, a forming member for forcing the hair down toward the base on each side of said projection, and means for retaining the forming member in clamping position.

6. In a device of the kind described, an elongated flat base member around which the strand of hair is adapted to be wound, a centrally arranged longitudinal relatively thin rib or projection on the upper face of the base, the lateral edges to the base being toothed, a slotted forming member adapted to be clamped upon the base at its ends and to hold the hair down on each side of said projection, and means for retaining the forming member in clamping position.

7. In a device of the kind described, an elongated flat base member having a central longitudinal rib on its upper edge, and having its lateral edges corrugated, a freely

separable forming member for forcing the hair down toward the base on each side of said projection, a socket at one end of the base for receiving one end of the forming member, and a slid able member on the opposite end of the base for engaging and disengaging the opposite end of the forming member and for retaining it in clamping position.

8. In a device of the kind described, an elongated base member having a central rib on its upper face and around which the strand of hair, to be waved, is adapted to be wound, a slotted forming member for forcing the hair down on each side of said central projection, the forming member having its ends offset downwardly to provide space beneath its middle portion for the hair being waved, and means for separably mounting the forming member upon the base.

In witness whereof I hereunto subscribe my name this 11th day of September, 1919.

BERNARD A. STERLING.
